PAINT CAN SHAKER

George L. Lee, Jr., Pittstown, N.J., assignor to Red Devil
Tools, Union, N.J., a corporation of New Jersey

Filed Dec. 11, 1961, Ser. No. 67,858

Term of patent 14 years

(Cl. D55—1)

FIGURE 1 is a front perspective view of a paint can shaker showing my new design;

FIGURE 2 is a top plan view thereof;

FIGURE 3 is a front elevational view thereof;

FIGURE 4 is a side elevational view of the left clamp element thereof;

FIGURE 5 is an elevational view of the opposite side of the clamp element shown in FIGURE 4;

FIGURE 6 is a top plan view of the clamp element shown in FIGURE 4;

FIGURE 7 is a front elevational view of the clamp element shown in FIGURE 4; and

FIGURE 8 is a rear elevational view of the clamp element shown in FIGURE 4.

The dominant features of my design reside in the portions shown in solid lines.

I claim:

The ornamental design for a paint can shaker, as shown and described.
